UNITED STATES PATENT OFFICE.

MYRON W. HOWARD, OF CAMANCIE, IOWA, ASSIGNOR OF ONE-HALF TO
JOHN L. ABBEY, OF SAME PLACE.

DESIGN FOR A FENCE-POST.

SPECIFICATION forming part of Design No. 26,990, dated April 27, 1897.

Application filed March 20, 1897. Serial No. 628,530. Term of patent 14 years.

To all whom it may concern:

Be it known that I, MYRON W. HOWARD, a citizen of the United States, residing at Camanche, in the county of Clinton and State 5 of Iowa, have invented or produced a new and original Design for Wire-Fence Posts, of which the following is a specification.

This invention has for its object to provide a novel and ornamental wire-fence post which 10 presents a peculiar and characteristic appearance.

The design consists in a fence-post having a disk-shaped foot-piece, a longitudinal V-shaped rib, and side flanges arranged at opposite sides of the rib, extending beyond the 15 apex or point of the said rib, and provided with a plurality of ornamental slots terminating in approximately circular eyes.

The invention is illustrated by the accompanying drawings, in which—

Figure 1 is a perspective view of the fence-post on a reduced scale, and Fig. 2 is a plan view of the same.

In the accompanying drawings the numeral

1 indicates the disk-shaped foot-piece, 2 the 25 longitudinal V-shaped rib, which extends continuously from the disk-shaped foot-piece to the top end of the post, and 3 the side flanges, arranged at opposite sides of the V-shaped rib and extending beyond the apex or point 30 4 of said rib, as clearly shown. The side flanges are each provided with a plurality of ornamental slots 5, extending from the edges of the flanges and terminating in approximately circular eyes 6.

The design provides an ornamental wire-fence post which presents a characteristic appearance.

What I claim is—

The design for a post, substantially as shown 40 and described.

In testimony whereof I have hereunto set my hand in presence of two subscribing witnesses.

MYRON W. HOWARD.
